SPOTTING BOARD FOR DRY CLEANERS

Frank M. Pilley, Wichita, Kans.

Application June 15, 1950, Serial No. 168,240

1 Claim. (Cl. 68—240)

1

This invention relates to cleaning equipment, particularly clothing and other fabric materials, and has to do with a relatively simple, inexpensive and time-saving device useable in cleaning establishments for spotting. A cleaning step commonly employed has an initial undertaking to remove soiling that requires special attention.

It is the most important object of the present invention to provide a spotting board of an elongated nature mounted upon a suitable pedestal, the board being longitudinally split presenting a pair of identical sections that are in turn mounted for swinging movement toward and away from each other.

Another object of this invention is to provide a sectional spotting board wherein the proximal, longitudinal edges of the elongated sections are movable to and from an abutting relationship as the same are swung on their common pedestal.

Other objects include the way in which the relatively swingable, identical sections are each provided with means for holding the same in a desired position with respect to the support; the way in which a portion of the innermost longitudinal edges of the sections are cut-away to permit the swinging movement and present a limiting stop; and the manner of inclining or arcuately contouring the outermost edges of the sections to adapt the same for the uses intended.

In the drawing:

Figure 1 is a top plan view of a spotting board for dry cleaners made pursuant to the present invention.

Fig. 2 is a side elevational view thereof.

Fig. 3 is a fragmentary, detailed, cross-sectional view taken on line III—III of Fig. 1; and

Fig. 4 is a fragmentary, inverted view of the uppermost cross bar of the support.

The component parts of the spotting board hereof include an elongated board broadly designated by the numeral 10, a vertical pedestal or upright support 12, and a base 14.

Base 14 is T-shaped and includes an elongated, flat cross-bar 16, an elongated stem 18 perpendicular to cross-bar 16 and overlapping the same intermediate the ends of cross-bar 16, together with a filler plate 20. Plate 20 underlies the stem 18 and abuts the proximal edge of the cross-bar 16 presenting a flat, lowermost surface when the portions 16, 18 and 20 of base 14 are suitably joined.

The support 12 may constitute an elongated, tubular member as illustrated in Figs. 2 and 3 threaded at both ends thereof to receive opposed flanges 22 and 24. Flange 24 is joined directly

5 with the stem 18 of base 14 directly above the cross member 16 by means of screws, bolts or the like 26. An elongated cross-head 28 rests upon the flange member 22 directly above the cross member 16 in parallelism therewith and is joined with the flange member 22 by screws or other fastening elements 30.

The elongated board 10 is horizontally disposed directly above the stem 18 and extends in the same direction as the latter from the pedestal 12. 10 Board 10 is split longitudinally to present a pair of identical sections 32 and 34, each having an innermost edge 36 that is straight throughout substantially the entire length thereof. Sections 15 32 and 34 are joined directly with the cross-head 28 for pivotal movement by means of bolt and nut assemblies 38 and 40 respectively. There is additionally provided a bolt 42 and a wing nut 44 for each section 32 and 34 respectively that passes 20 downwardly therethrough in spaced relationship to the corresponding pivotal bolts 38 or 40 in the manner shown by Fig. 3 of the drawing. Bolts 42 also pass through a corresponding elongated, arcuate slot 46 formed in the cross-head 28. 25 That end of the edges 36 of sections 32 and 34 next adjacent the cross-head 28, are cut-away as at 48 presenting a V-shaped notch as shown in Fig. 1 when the edges 36 of sections 32 and 34 are in abutting interengagement. When the edges 36 are separated however, with the sections 32 and 34 swinging on their corresponding axes 38 and 40, the cut-away edges 48 are brought into abutment in the manner illustrated by dotted lines in Fig. 1 of the drawing.

30 35 While the outermost longitudinal edges of the board 10 are straight through substantially the entire length thereof, the same are formed in a slit taper 50 adjacent that end of the board 10 opposite to cross-head 28, which tapered portions 50 converge as the outermost free ends of the sections 32 and 34 are approached. Such tapered edges 50 merge into a rounded end 52 for each section 32 and 34 respectively that in turn merges with the straight innermost longitudinal edges 36.

40 45 The board 10 may either be used in the manner illustrated by full lines in Fig. 1 of the drawing, with the sections 32 and 34 together and with the edges 36 in abutment, or with the sections 32 and 34 separated to any distance desired within the limits defined by the cut-away portions 48.

50 55 One example of use is in the spotting of trousers or other garments having tubular portions such as coats, blouses and the like. When such fabric materials are to be spotted, the garment is placed over the sections 32 and 34 extending into the legs

of the pants or the sleeves of the coat as the case may be. As long as the wing nuts 44 are loosened, the sections 32 and 34 are freely swingable with respect to each other and if desired, when the trousers are threaded thereon, sections 32 and 34 can be spread to hold the material in a convenient condition to be worked. The wing nuts 44 may be tightened to hold the sections of board 10 against swinging movement. The most practical way of setting nuts 44 is to tighten one and allow the other to remain loose. Alternately, relatively flat garments can be placed upon the board 10 when the same is in the condition shown in full lines of Fig. 1 for spotting of the fabric or otherwise treating the same such as in pressing and cleaning operations.

Another feature that pertains to the desirability of the straight edges 36 and their abutting engagement, is that the garments threaded upon the sections 32 and 34 may be clamped in place with portions thereof disposed between edges 36 and with the wing nuts 44 clamped in place. Free swinging movement of the sections 32 and 34 is presented while maintaining the desired feature of abutment between edges 36 because of the cut-away portions 48. The tapered edges 50, together with the rounded ends 52 facilitate the threading of the garments upon sections 32 and 34. If only one leg of a pair of trousers for instance, is to be "spotted," the entire garment may nevertheless be positioned upon the sections 32 and 34, thereby holding all of the material in a suspended condition off of the floor and eliminating the necessity of underlying structure as a support.

The entire assembly is easy to use, inexpensive to manufacture and adaptable to save considerable time in the initial and/or final spotting operations or other tasks that must be hand-performed in dry cleaning processes. By virtue of the position of pedestal 12 and the arrangement of base 14, the device is accurately balanced and there are no parts adjacent the board 10 that would tend to interfere with the use of sections 32 and 34.

Many advantages other than those above set forth will emanate from use of the spotting board hereof and it is therefore, desired to be limited only by the spirit of this invention as defined by the scope of the appended claim.

Having thus described the invention, what is claimed as new and desired to be secured by Letters Patent is:

A spotting board comprising a standard; an elongated, flat, horizontal cross-head fixed to said standard, said cross-head having an arcuate slot formed therein adjacent each end thereof respectively; an elongated, horizontal panel on said cross-head having a V-shaped notch formed in one end thereof, said panel being longitudinally split from the apex of said notch to the opposite end of the panel, presenting a pair of side-by-side sections, the sections each being pivotally secured to said cross-head adjacent said notch for swinging movement to and from a position with the proximal longitudinal edges thereof in abutting relationship; and a releasable bolt and nut assembly on each section respectively and extending through the corresponding arcuate slot for limiting the swinging movement of the sections toward and away from each other, said notch being disposed to limit the extent of movement of the sections away from each other.
